UNITED STATES PATENT OFFICE.

AUGUST T. WEHRLE, OF NEWARK, OHIO.

DESIGN FOR A STOVE.

No. 38,498.

Specification for Design.

Patented March 26, 1907.

Application filed February 20, 1907. Serial No. 358,506. Term of patent 7 years.

To all whom it may concern:

Be it known that I, AUGUST T. WEHRLE, a citizen of the United States, residing at Newark, in the county of Licking and State of Ohio, have invented a new, original, and ornamental Design for Stoves, of which the following is a specification, reference being had to the accompanying drawing, forming part thereof.

My invention is shown in the accompany-

ing drawing, in which the stove is shown by a single figure, in front perspective, illustrating the design of my invention.

I claim—

The ornamental design for a stove substantially as shown.

AUG. T. WEHRLE.
